DRAPEY FIXTURE

Walter H. Toelle and Frank R. Ulbrich, Wallingford, Conn., assignors to H. L. Judd Company, Wallingford, Conn., a corporation of Delaware

Application May 3, 1945, Serial No. 591,680

2 Claims. (Cl. 211—105.2)

1

Our invention relates to a drapery fixture.

It is an object of the invention to provide an improved drapery fixture particularly adapted for embodiment in a crane.

It is another object to provide a drapery fixture for embodiment in a crane or the like, which is sturdy in construction so as to hold a rod against sagging and which is relatively simple and cheap to manufacture.

Other objects are to provide improved details of construction for embodiment in drapery fixtures, particularly though not exclusively cranes.

In the drawings which show, for illustrative purposes only, a preferred form of the invention—

Fig. 1 is a view in side elevation of a drapery fixture illustrative of the invention and showing a flat rod in section;

Fig. 2 is a sectional plan view, taken substantially in the planes of the broken line 2—2 of Fig. 1;

Fig. 3 is a sectional view taken substantially in the plane of the line 3—3 of Fig. 1;

Fig. 4 is an isometric view of a plate forming part of a rod bracket;

Fig. 5 is a similar view of a plate or shoe forming another part of a rod bracket.

Briefly stated, in a preferred form of the invention I provide a wall bracket to be secured to a wall or window casing and a rod bracket to carry a crane arm preferably in the form of a flat rod. The rod bracket and wall bracket are so connected as by means of a link that the crane arm may be adjusted toward and from the wall and may be adjusted angularly relatively to the wall.

In the specific embodiment illustrated, the wall bracket 5 may consist of a generally U-shaped extension plate 6 having feet 7—7 to be secured to a wall as by means of screws 8, as will be understood. The U-shaped horizontally extending arm 6 may be provided with slots 9 for adjustment, as will appear. The wall bracket preferably includes a plate 10 which may be embraced by the U-shaped arm 6 so that it may be moved in and out of the U-shaped arm 6 and means such as screws 11—11 may be threaded into tapped apertures in the plate 10 so that the heads ride on the arm 6 at the outsides of the slots 9. Thus, when the screws 11 are loosened, the plate 10 may be moved horizontally outwardly or inwardly relatively to the wall and the plate may be secured in any adjusted position by tightening up the screws 11. The plate 10 has ears for supporting a pintle and in the form shown the outer end of

2

the plate is provided with an angularly extending flange 12 having upper and lower horizontally extending ears 13—13. A pintle 14 is secured between the ears and is preferably in the form of a pin riveted or otherwise secured to the ears so as to stand in a vertical position during normal use.

The rod bracket 15 supports a crane arm preferably in the form of a more or less standard flat

rod 16. Such a flat rod may be of substantially C-shaped cross-section and at the rear side has a longitudinally extending slot 17, as is common. The rod bracket 15, which supports the flat rod 16, preferably includes a flat plate 18 which is

15 of substantially greater width than the slot 17 in the rod so as to fully span the latter and each plate 18 extends longitudinally of the rod a sufficient distance to form a relatively rigid support, as will be described. At the inside of the rod is

20 a second plate, or what may be termed a shoe 19, which is of greater width than the slot 17 in the rod, and this shoe 19 extends longitudinally of the rod for a substantial distance. The plates 18—19 are secured together as by means of a

25 screw 20 and are provided with interfitting parts extending through the slot. In the form illustrated, the shoe 19 has outwardly projecting flanges 21—21, which are of a width to just fit the slot. The other plate 18 is provided with

30 apertures 22—22 for receiving the ends of the flanges 21—21. Thus, with the flanges 21—21 of a width to just fit the slot 17 nicely and of a width to substantially fill the diameter of the holes 22—22, there can be no substantial rotation be-

35 tween the rod and the plates 18—19 and since the flanges 21—21 which resist rotation are spaced apart a considerable distance along the rod, there is little or no tendency for the rod to sag when in use. The rod bracket plate 18 is preferably

40 provided with horizontally extending ears 23—23, which may be formed like the ears 13—13 on the wall bracket or, as illustrated, by a separate U-shaped member 24, which may be riveted or otherwise secured to the plate 18 as indicated at 25.

45 The ears 23—23 carry a vertically extending pintle 26, which may be and preferably is of the same character as the pintle 14 and may be riveted or otherwise secured or attached to the ears 23—23.

Now, in order to support the crane arm 16 from 50 the wall bracket, I employ a link 27. The link preferably consists of two plates 28—28 which are positioned vertically so as to be very stiff to resist sagging of the crane arm. One or both of the plates are formed so as to embrace the pintles 14 and 26, and in the form illustrated

each of the plates at each end is provided with an arcuate transversely extending groove 29 for embracing pintles 14 and 26. The plates 28-28 are secured together as by means of one or more screws 30. Thus, the friction between the link 27 and the pintles 14-26 may be nicely adjusted by adjusting the screws 30. Of course the two plates 28 could be riveted together and reliance placed on the resiliency of the metal of the plates to provide frictional resistance to turning of the pintles in the link ends.

It will be seen that the crane arm may be moved in and out relatively to the wall, first by adjustment of the wall bracket, if such an adjustable bracket is employed, and, second, by swinging the arm about the pintles. Three positions of the crane arm have been indicated in Fig. 2. It will be apparent that the crane arm may also be swung angularly if it is desired to have the crane arm positioned angularly relatively to the wall rather than parallel to the wall as illustrated. The drapery fixture is of a sturdy construction, and due to long, vertically extending pintles and girderlike construction of the link 28, there will be no sagging of the crane arm regardless of its position of adjustment.

While the invention has been described in considerable detail and a preferred form illustrated, it is to be understood that many changes may be made within the scope of the invention as defined in the appended claims.

We claim:

1. In a device of the character indicated, a wall

bracket including horizontally extending spaced ears, a pintle pin positioned vertically and held by said ears, a rod bracket having horizontally extending spaced ears, a pintle extending vertically and held by said last mentioned ears, a link for connecting said pintles, said link comprising plates positioned in vertical planes and at their ends embracing said pintles, and means for securing said plates to each other.
